UNITED STATES PATENT OFFICE.

CLAUDIA MOORE, OF SEATTLE, WASHINGTON.

DESIGN FOR A SET OF ALPHABET-CARDS.

• 56,985.

Specification for Design.

Patented Jan. 25, 1921.

Application filed July 27, 1920. Serial No. 399,408. Term of patent 14 years.

To all whom it may concern:

Be it known that I, CLAUDIA MOORE, a citizen of the United States, residing at 3624 Burke avenue, Seattle, in the county of King and State of Washington, have invented a new, original, and ornamental Design for a Set of Alphabet-Cards, of which the following is a specification, reference being had to the accompanying drawing, forming part thereof.

The drawings except for the lower right hand card illustrate the obverse side of a set of alphabet cards showing my new design. The lower right hand card illustrates the reverse side of the cards in the set.

I claim:

The ornamental design for a set of alphabet cards, as shown.

CLAUDIA MOORE.
